UNITED STATES PATENT OFFICE.

CHRISTOPHER LOSETH, OF COUNCIL BLUFFS, IOWA.

DRIVE-ANCHOR.

1,273,890.

Specification of Letters Patent. Patented July 30, 1918.

Application filed May 13, 1916. Serial No. 97,434.

To all whom it may concern:

Be it known that I, CHRISTOPHER LOSETH, a citizen of the United States, residing at Council Bluffs, in the county of Pottawattamie, State of Iowa, have invented a new and useful Drive-Anchor, of which the following is a specification.

My invention relates to improvements in anchors for anchoring cables at various depths and which after being driven are adapted to open, thus increasing their anchorage properties, and the objects of my invention are:

First: To provide a suitable land anchor which can be driven to any reasonable depth to engage suitable resisting soil without undue force.

Second: To provide such an anchor that the driving instrumentality may be removed and used again.

Third: To provide such an anchor without an extended shank.

Fourth: To produce such an anchor as will automatically increase its anchorage powers.

Fifth: To provide a means for positively causing the arms of said anchor to open and increase the resistance to pull upon the cable.

Sixth: To provide such an anchor that will be cheap in its construction and simple in its parts.

I attain these objects by the device illustrated in the accompanying drawing in which:

Figure 1 is a side elevation of the anchor head with the driving tube shown in section, the arms of the anchor being closed. Fig. 2 is a side elevation of the said anchor and driving tube with vanes open. Fig. 3 is a side elevation of the anchor taken at right angles to the elevation shown in Fig. 2, but showing the anchor arms closed. Fig. 4 is an elevation of the anchor head shown in Fig. 2, but at right angles thereto and without the driving tube attached. Fig. 5 is a cross section of the anchor head showing the method of attaching the anchor arms. Fig. 6 is a side elevation of the anchor arms detached. Fig. 7 is a plan of the anchor arms detached. Fig. 8 shows a method of fastening the cable into the shank.

Similar letters refer to similar parts throughout the several views.

In many cases in engineering it is desirable to anchor cables into the soil both under the water and on land. It is necessary in some cases to go through a sand or silt

into a heavier body of earth, as clay or gravelly earth. In providing such anchorage it is desirable to use the least possible material and to avoid long anchor shanks so that the cables may be free to take their own direction from the point of application of the anchor head. A sharpened anchor head *h* is provided with a smaller reduced portion or shank *s* to which is attached a cable *c*.

While here only a cable is shown it may consist of a rope, steel cable or chain and is fastened into the shank *s* through a hole in the said shank or in any suitable manner. When a steel cable or chain is used it may be cast into the anchor shank as shown in Fig. 8. The shank *s* is adapted to fit into a suitable sized commercial pipe or tube *a* which may be of any suitable length. A driving cap *k* may be threaded or driven on to the pipe *a* and a slot provided below said cap *k* for the cable *c* and the cable *c* may thereby be made any length with respect to the driving pipe *a*. Anchor arms *b* and *b'* are provided which are hinged in the head *h* and are arranged when closed to occupy hollowed spaces provided in the head as shown in Fig. 1. The arms *b* and *b'* are arranged to each fold into the recess of the anchor head and to turn outward at some suitable angle herein shown at right angles for convenience; the said arms are formed so that the head holds them at the proper angle. The fins *f* and *f'* of sufficient length, but of a thickness not to interfere with the driving of the head, may be arranged to further strengthen the anchor arms when open. The points or ends of the anchor arms *b* and *b'* are slightly curved so as to throw themselves into the earth when it is attempted to withdraw the anchor by pulling on the cable. In addition to the curving ends of the anchor arms *b* and *b'* simple springs as *p* and *p'* may be provided to give the arms a tendency to be thrown outward when the anchor head is drawn backward. The anchor arms *b* and *b'* are preferably formed having a hinged joint as shown in Figs. 6 and 7 though the particular joint or manner of connecting the said arms to the head is not controlling in the invention.

The driving pipe *a* is free to be removed from the shank *s* when the anchor head *h* has been driven or forced down to its depth.

The anchor head *h* with the cable *c* attached is placed in a driving pipe *a* having

a suitable driving head *h*. Several sets of tubes *a* of different lengths may be used for various depths. The anchor is then driven to the depth required by striking or driving 6 upon the head *h* or an ordinary commercial pipe or tube may be used with the cable passed through and a pile driver head laid over the same with a suitable hammer adapted to drive the same into the ground. 10 This anchor may be driven into the bottom of rivers, harbors or other places where it is necessary to go through silt and sand and reaching clay or more solid soil, or it may be driven along banks in rivers, or a means 15 of fastening guy wires or cables. After the anchor is driven to place the driving tube may be withdrawn if desired, the cable passing through it, or it may be cut off at the top of the ground or water and filled with a 20 composition to preserve the cable. When the pull is put upon the cable after being driven the anchor arms *b* and *b'* will by reason of the shape of the ends thereof and aided by the springs *p* and *p'* open and engage 25 the soil through which the anchor head has passed. The anchor head will then move until the anchor arms have reached the extremity of their movement in the head *h* or to the position shown in Fig. 2 and the anchor 30 will then offer all the resistance that

said arms can give in the soil in which it is placed. These anchors may be made of various sizes with various lengths and areas of arms adapted to various soils and varying 35 sized cables.

I am aware that land anchors have been heretofore made having movable hinged arms and adapted to being driven into the soil, but what I claim and desire to secure 40 by Letters Patent is:

A drive anchor comprising a body provided with an arrow shaped head and having an opening thereat, said body being also provided at opposite sides with depressed portions or recesses and having longitudinal 45 grooves extending from the same to the said opening, arms pivoted within the said opening and extending along the grooves and provided with curved terminal portions located within said recesses or depressed portions and terminating short of the inner ends of the same to expose the ends of the arms which are deflected laterally and offset from the walls of the recesses or depressions to facilitate their engagement and springs ar 50 ranged to urge the arms outwardly.

CHRIS. LOSETH.
